UNITED STATES PATENT OFFICE.

KARL F. W. KOCH, OF CHICAGO, ILLINOIS.

SPADING-PLATE FOR WATERPROOF FOOTWEAR.

1,152,185.

Specification of Letters Patent. Patented Aug. 31, 1915.

Application filed October 5, 1914. Serial No. 864,969.

To all whom it may concern:

Be it known that I, KARL F. W. KOCH, a citizen of the United States, residing at Chicago, in the county of Cook and State 5 of Illinois, have invented certain new and useful Improvements in Spading-Plates for Waterproof Footwear, of which the following is a specification.

My invention relates to spading plates for 10 waterproof foot wear, and particularly relates to a plate which may be applied to the under side of a waterproof boot or shoe to protect the same from abuse caused by the use of spades or shovels, or otherwise.

15 Heretofore when doing heavy spading or shoveling in wet ground men have been in the habit of wearing heavy leather-soled rubber boots which, besides being very heavy and clumsy, have been considerably 20 more costly than ordinary rubber foot wear. There is at the present time an increasing demand for boots which, besides being lighter, shall be much less expensive than the customary heavy leather-soled boot.

25 Certain improved modern processes, such as the vacuum process, for the production of rubber goods have resulted in very great improvements in the wearing qualities of rubber boots, and at the present time it 30 would be quite feasible to manufacture a rubber boot for the use of laborers operating spades and shovels if it were not for the fact that the shank of the shoe is unable to stand up under the abuse of the spade or 35 shovel when the foot is used to assist in the operation. On this account workmen either hesitate to employ the under side of the ordinary boot to assist in such manipulation of the spade or shovel, thus operating at re-

40 duced efficiency, or they still purchase the heavy leather-soled boots which, as before stated, are very expensive besides being clumsy and hard on the feet. Some desultory attempts have been made to apply 45 protective plates to shoes, but, so far as I am aware, such attempts have been confined to ordinary boots and shoes and have resulted in devices which have either rendered the boot heavy and clumsy or have impaired 50 its waterproof properties.

The salient objects of my invention are, to provide a construction in which a protective metal plate is securely applied to the under side of a waterproof boot or shoe for 55 the purpose of protecting the latter from injury; to provide a construction of the class

described in which the plate if desired may be applied only to that part of the shoe which receives the most wear and where it does not seriously if at all interfere with the flexible character of the sole; to provide a 60 construction of the class described which results in practically no increase in weight over that of the ordinary boot or shoe unprovided with such a protector; to provide a construction in which the said plate is securely attached to the shoe or boot without the use of extraneous fastenings, which might be liable to become broken or displaced or cause an accumulation of foreign 65 matter; to provide a construction of the type referred to in which the metal plate is located entirely or almost entirely below the upper of the boot or shoe so as not to interfere with the free movement of the foot inside the shoe or cause the upper portion of 70 the shoe to present an unsightly appearance; to provide a construction in which the plate is securely united to the shoe by means of a member or members 75 embedded in the rubber of the shoe during the process of manufacture so that the shoe loses none of the waterproof characteristics 80 of ordinary rubber foot wear; to provide a construction in which the anchoring means for the plate is integrally built into the shoe 85 or boot during the process of forming the latter prior to vulcanization, and afterward vulcanizing the assembly in its final position; to provide a construction in which the 90 entire shoe, anchoring means and protective plate may be assembled and united together before the shoe is vulcanized, thereby to obtain a perfectly secure and waterproof connection between the various parts 95 of the shoe; to provide a construction which shall be simple and economical in manufacture, and, in general, to provide an improved construction of the class referred to.

In describing my invention, I prefer to 100 illustrate it by means of the accompanying drawings which show a practical embodiment of my invention as applied to a rubber boot of the type usually worn by well-diggers or sewer-excavators when working in 105 wet ground.

In the drawings—Figure 1 is a side elevation of a boot; Fig. 2 is a section taken longitudinally on a vertical plane through the center of the lower portion of the boot; 110 Fig. 3 is a fragmentary section taken on the line 3—3 of Fig. 2; Fig 4 is a plan

view of the metal anchor plate, and Fig. 5 is a plan view of a spading plate.

Referring to the drawings, 10 designates as a whole a rubber boot to the under side of which my improved wear plate is applied, this boot being of the usual type built up of layers of rubber compound and canvas, and then vulcanized. Referring to Fig. 2, it will be seen that the wear or spading plate 11, which in this instance I have shown as extending from the heel of the shoe forward substantially to the end of the shank, is secured to the shoe without the aid of extraneous fastening devices, the connection being obtained by means of a plurality of rivets or pins 12 which extend into the shank of the boot and are there united to an anchor plate 13. This anchor plate 13 is preferably incorporated into the shank of the shoe during the process of manufacture and in the following manner: The first step in the process of building up the bottom of the shoe upon the last consists in the application to the last of the prepared canvas insole 14. The operator then applies to the canvas insole in the region of the shank a sheet rubber packing piece 15 which has an area considerably greater than that of the anchor plate 13. The next step is to apply the anchor plate 13, to which the four rivets 12 have been previously united. It will be noticed that the said rivets 12 where they enter the anchor plate 13 are considerably reduced in cross section so as to form shoulders, which prevent longitudinal movement of the rivets in the anchor plate 13 while the outer wear plate 11 is being riveted in place. After the anchor plate 13 has been placed in position, a second rubber sheet 16 is forced over it, this rubber sheet being somewhat longer than the rubber packing sheet 15 and substantially of the same width. It should be noted that in applying the sheet 16 and the succeeding layers, holes are not previously formed to admit the rivets which make their own holes when the rubber or canvas sheets are applied. This insures a snug fit between the rivets and the layers through which they pass, due to the resiliency of the material of which said layers are composed. After the second rubber sheet 16 has been placed in position the heel and sole of the shoe are built up to the same level as the shank by adding fillers 17, which fillers comprise layers of canvas or other fabric to which has been applied a coating or filling of rubber compound. It should be noted, however, that the rubber sheets inclosing the anchor plate 13 are made of a grade of rubber considerably higher than that of the fillers 17. Having built up the under side of the shoe to a substantially equal thickness throughout its length, a second set of fillers 18 and 19 is

applied prior to the attachment of the sole and heel 20 and 21. These latter are carried by a comparatively thin sheet 22, the outer edges of which extend for some distance beyond the outline of the sole and heel and are folded up over the lower edge of the upper 23, as shown. Although under some circumstances it might be desirable to defer the application of the wear plate 11 until vulcanization of the boot was effected. I prefer to apply the said plate and rivet it in position before the shoe is vulcanized so that there is no possibility of injuring the parts of the completed shoe during the said riveting operation, and, in addition, because when the plate is riveted in position before vulcanizing the whole assembly is tightly squeezed together and becomes a coherent unitary structure during the vulcanizing process. In order to render the anchoring means 13 still more effective I form therein a plurality of apertures 24 which are filled with a rubber compound during the process of building up the shoe. Thus, when the shoe is vulcanized, this compound becomes vulcanized and united to the rubber sheets on either side of the anchor plate 13, the outer margins of the said sheets 15 and 16 also becoming securely vulcanized together. I prefer to employ the vacuum process during the vulcanization of the shoe or boot, which process I have found secures an extremely dense and tough body of rubber free from blow holes or other defects.

In order to make the spading plate 11 more effective when used in conjunction with the spade or shovel, I form therein a series of corrugations 25 which prevent the edge of the spade or shovel from sliding along the wear plate. I also form the spading plate with a downwardly projecting right-angle flange 26 which coincides with and lies along the front edge of the heel 21 thus protecting the latter from the abuse of the shovel and at the same time reinforcing it substantially. The plates 11 and 13 are preferably constructed of stiff sheet metal by means of suitable dies, and the formation of the corrugations in the under side of the plate 11 thus results in the formation of corresponding depressions 27 on the under side thereof into which the rubber of the shank is forced when the wear plate is riveted in position prior to vulcanization. This feature assists materially in preventing longitudinal movement of the wear plate, without placing too much dependence upon the stiffness of the rivets 12. It should be noted also that the side edges of the spading plate 11 are flanged up to conform with and hug the side of the shank, as shown at 28, thus to a certain extent protecting the sides of the shank while at the same time assisting in the prevention of lateral movement of the spading plate.

Although I have shown a wear plate which is primarily adapted to prevent abuse caused by the use of a spade or shovel, it will be obvious that the plate could be made 5 considerably larger in area so as to protect practically the entire area of the under side of the boot, if found desirable. It will also be apparent to those skilled in the art that my construction in no way impairs the 10 waterproof quality of the boot owing to the manner in which the parts are incorporated into the material of the boot, and this results in a simple, neat and economical construction which is particularly well designed to 15 carry out the purpose and fulfill the objects previously set forth.

It will be manifest to those skilled in the art that although I have described what I consider to be a preferred embodiment of 20 the novel features of my invention, yet the details may be varied considerably without sacrificing any of the advantages or benefits thereof, and consequently I do not wish to be limited in the use of my invention, except 25 as specified in the appended claims.

I claim—

1. The combination of an article of foot wear provided with a base including a pair of overlying sheets of a rubber compound, a 30 sheet metal anchor plate inserted between said sheets, rivets secured in said anchor plate and projecting through the lower sheet and extending to the outer lower surface of the base, and a metal wear plate secured to the outer ends of said rivets, said wear plate being provided with a pair of upstanding side flanges embracing the base, and a downwardly projecting rear end flange adjacent the front end of the heel.
2. In rubber foot wear, the combination 40 with the base provided with two distinct superposed horizontal layers of rubber com-

pound, of a horizontally disposed anchor plate inserted between said layers prior to vulcanization of the base, a connecting member secured to and extending from said anchor plate outwardly through the bottom layer, and an outer plate secured to the lower end of said connecting member. 45

3. In rubber foot wear, the combination 50 with the base provided with two distinct superposed layers of rubber compound, a horizontally disposed anchor plate of extended area, provided with openings therein and inserted between said layers prior to 55 vulcanization of the base, a connecting member extending substantially at right angles to said plate outwardly through the bottom layer, an outer plate secured to the lower outer end of said connecting member, and a 60 rubber filling compound contained within the openings of said anchor plate and adapted to form connections between said layers upon vulcanization of said base.

4. In rubber foot wear, the combination 65 with the shank provided with an upper layer of rubber compound and a lower layer composed of rubber and fabric and extending over the heel and sole on either side of the shank, a perforated anchor plate horizontally disposed between said layers and located between them prior to vulcanization 70 of the base, pins extending from the outer lower surface of the shank transversely through said lower layer and rigidly united 75 to said anchor plate, an outer wear plate secured to the outer lower ends of said pins, and a rubber filling material inserted in said perforations and united to said layers by vulcanization.
